Primary Examiner — Austin Murphy*(74) Attorney, Agent, or Firm* — Cantor Colburn LLP(57) **CLAIM**

The ornamental design for a handle for tablet PC, as shown and described.

DESCRIPTION

FIG. 1 is a perspective view of a handle for tablet PC showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a reference view thereof when in use;

FIG. 9 is another reference view thereof when in use; and,

FIG. 10 is a cross-sectional view thereof taken along line 10-10 of FIG. 2.

The broken lines are shown for environmental structures when in use and form no part of the claimed design.
